NEGATIVE TRANSCONDUCTANCE DEVICE
AND CIRCUITMurray G. Crosby, Riverhead, N. Y., assignor to
Radio Corporation of America, a corporation
of Delaware

Application November 26, 1941, Serial No. 420,500

5 Claims. (Cl. 250—36)

This invention relates generally to electron discharge device circuits employing the negative transconductance phenomenon.

The term "transconductance" is used in the art to indicate the change in anode current per volt increase of grid potential. In the conventional type of evacuated electron discharge device or vacuum tube, a rising positive potential on the control electrode causes an increase in the electron current to the output electrode, usually the anode. Such a device is said to possess positive transconductance. In another type of evacuated electron discharge device, a rising positive potential on the control electrode causes a decrease in the electron current to the output electrode. This last type of device is said to possess negative transconductance. It will thus be seen that the difference between positive and negative transconductance lies solely in the direction of change of the current in the anode or output electrode per volt increase of potential on the control electrode. Both of these types of devices may be used either as amplifiers or oscillation generators.

The primary object of the present invention is to provide a negative transconductance device and circuit which requires fewer circuit elements than prior structures.

A further object of the present invention is to provide a negative transconductance device which has a high output impedance and a relatively high gain.

A further object is to provide a negative transconductance device in the form of a pentagrid electron discharge device whose screen grid circuit employs an unbypassed resistor.

A more detailed description of the invention follows in conjunction with the drawing, wherein Figs. 1, 2 and 4 illustrate, by way of example, two amplifier circuits embodying the principles of the present invention, and Fig. 3 illustrates an oscillation generator embodying the principles of the present invention.

Referring to Fig. 1, there is shown an amplifier negative transconductance device in the form of a pentagrid vacuum tube 1 having a cathode K, a control grid G₁, a second grid G₂, a third grid G₃, a fourth grid G₄, a suppressor grid G₅ and an anode or plate P. Grids G₂ and G₄ are connected together to form a screening circuit for the grid G₃, the latter being directly connected to ground by means of connection 2. The cathode is provided with a self-bias or grid-bias resistor r which, if desired, may be bypassed by a suitable condenser. The first grid G₁ or control

electrode is connected to a suitable input circuit as shown. The screen circuit comprising grids G₂ and G₄ is connected to an unbypassed resistor R and thence to the positive terminal of a source of unidirectional potential. The anode or plate P is connected to one side of an output circuit whose other side is also connected to the same positive terminal of the source of unidirectional potential.

10 In the operation of the amplifier of Fig. 1, an increase in positive potential on the control grid G₁ will cause an increased flow of electrons from the cathode K to the screen grid circuit G₂, G₄, as a consequence of which there will be an increased current flowing in the unbypassed resistor R. This increased current through resistor R will cause an increased IR drop in the screen circuit, as a consequence of which there will be less positive potential on the grids G₂ and G₄; or, putting it another way, an increased electron current flow from the cathode will cause a decreased positive potential to appear on the screen grids G₂ and G₄. This decrease in positive potential on the screens G₂ and G₄ will prevent many of the electrons from reaching the plate or anode P, as a consequence of which there will be less current in the plate circuit and an increase of positive potential on the plate P. From what has been said above, it will thus be 20 evident that a rising potential on the control electrode G₁ causes a decrease in the electron current to the output electrode P.

From an inspection of Fig. 1, it will be noted that applicant obtains a negative transconductance device with fewer circuit elements than customarily employed in known types of negative transconductance devices. The circuit of Fig. 1 is advantageous when used at audio frequencies because of the high output impedance and the relatively high gain obtainable.

40 Although I have shown the screen circuit and the plate circuit coupled to the same source of positive polarizing potential, the circuit of the invention is not limited thereto since the screen and plate circuits can employ separate sources of polarizing potential.

The circuit of Fig. 1 is especially useful at audio frequencies for the reasons mentioned above, but at higher frequencies it suffers from a disadvantage because the resistor R is shunted or bypassed by the screen-to-ground capacity. In order to employ the principles of the present invention at frequencies higher than audio frequencies, I propose replacing the resistor R of Fig. 1 by 50 a tuned circuit Z as shown in Fig. 2, to thereby

tune out the screen to ground capacity. The circuit Z is tuned to the frequency of the input waves and comprises a condenser and an inductance in electrically parallel relation. The tuned circuit Z is thus a substantially pure resistance at the operating frequency because it is anti-resonant, and in this way I am able to obtain the necessary IR drop in the screen circuit, in response to a rise or fall in potential on the control grid. The circuit will also function by shunting the resistor R with the tuned circuit Z, in which case the tuned circuit would be damped by resistor R.

Fig. 3 illustrates how the principles of the present invention can be applied to an oscillation generator. In Fig. 3, the parallel tuned circuit L, C is the output circuit. A feed back condenser C₁ is connected between the output tuned circuit and the first or control grid G₁ for feeding back energy from the plate which is in phase with the voltage on the control grid. The resistor R₁ is the grid return resistor. With the circuit as shown in this figure, oscillations will be maintained as long as the frequency is not high enough to enable the screen to ground capacity of the vacuum tube to bypass the screen resistor R. Here again, if it is desired to employ the oscillation generator at high frequencies, I may tune out the screen to ground capacity by replacing the resistor R with a tuned circuit Z, in the manner shown in Fig. 2.

The oscillator of Fig. 3 can be converted into a multivibrator circuit by replacing the tuned circuit L, C with a resistance. If this resistance is made small compared to the constants of R₁ and C₁, then the grid return resistor R₁ and condenser C₁ will determine the frequency of the relaxation oscillations.

Fig. 4 illustrates a modification of Fig. 1, wherein in the multi-grid vacuum tube 1 is replaced by a four-electrode screen grid tube 1'. The operation of the circuit of Fig. 4 will be apparent from the description given above for Fig. 1.

I have found that a practical negative resistance device in accordance with the invention may comprise an RCA 6-L-7 tube with 170,000 ohms in the screen circuit for resistor R and 800 ohms for the cathode circuit for the resistor r. With such a circuit, bypassing of the cathode resistor seems to have very little effect on the operation of the circuit.

Although the invention has been described with particular reference to a pentagrid vacuum tube, it should be understood that the invention is not limited to the use of such a tube, since, if desired, a screen grid or four-electrode tube can be employed in accordance with my teachings without departing from the spirit and scope of the invention.

What is claimed is:

1. An electron discharge device oscillation generator system obtaining negative transconductance between input and output electrodes, comprising an evacuated envelope having therein a cathode, a control electrode as an input electrode, a screen electrode, and an output electrode, a connection from said screen electrode to the positive terminal of a source of unidirectional potential, a parallel tuned circuit tuned to the operating frequency of said generator connected between the output electrode and said positive terminal of said source of unidirectional potential, an impedance circuit substantially resistive at the operating frequency in said connection between the screen electrode and said source of unidirectional potential, said impedance circuit having sufficiently high

value to produce the negative transconductance effect, a feed-back circuit consisting of a condenser connected between said output electrode and said input electrode for feeding back energy from said output electrode which is in phase with the voltage on the input electrode, and a resistor connected between said input electrode and said cathode.

2. A negative resistance adapted to produce oscillations when connected across a resonant circuit of relatively low frequency, comprising a vacuum tube having in the order named, a cathode, a control electrode, a grid, a screen and an output electrode, a resistor connecting said cathode to ground, a connection from said output electrode to one terminal of said resonant circuit, a capacitive connection from the grounded end of said resistor to the other terminal of said resonant circuit, an unbypassed resistor connected between said screen and said last terminal of said resonant circuit, and a connection from said last terminal to the positive terminal of a source of unidirectional potential, said unbypassed resistor being of a value sufficiently high to produce the negative transconductance effect, a direct connection between said grid and ground, a resistor between said control electrode and the grounded end of said first resistor, and a feed back circuit between said output and control electrodes for capacitively feeding back energy from the output electrode which is in phase with the voltage on the control electrode, said feed back circuit being devoid of inductance coupling effects.

3. An electron discharge device oscillator system utilizing the negative transconductance phenomena, said device having a cathode, an input electrode, a screen electrode, and an output electrode; a connection having substantially purely resistive impedance of a sufficiently high resistance to produce the negative transconductance effect at the operating frequency between said screen electrode and the positive terminal of a source of unidirectional potential, a feed back circuit devoid of inductive coupling and comprising a condenser coupled between said output and input electrodes, and a tuned output circuit tuned to the operating frequency of said oscillator system coupled between said output electrode and cathode, a resistor connected between said input electrode and said cathode, whereby a rising positive potential on said input electrode causes a decrease in the electron current to said output electrode.

4. An electron discharge device oscillator system obtaining negative transconductance between input and output electrodes, comprising a pentagrid tube having a first grid as an input electrode and an anode as an output electrode, a direct connection between the second and fourth grids to constitute a screen for the third grid, a direct connection between the fifth grid and the cathode, a direct connection between the third grid and ground, a connection having substantially purely resistive impedance of a sufficiently high value to produce the negative transconductance effect at the operating frequency extending from the screen to the positive terminal of a source of unidirectional potential whose negative terminal is connected to ground, a resistor of relatively small value connected between said cathode and ground, a parallel tuned output circuit connected between said output electrode and the positive terminal of a source of polarizing potential, a capacity feed back circuit devoid of inductive coupling effects connected between said output and input elec-

trodes, and a resistor connected between said input electrode and ground.

5. An electron discharge device oscillator system obtaining negative transconductance, comprising a vacuum tube having therein a cathode, a first grid, a second grid, a screen grid, and an anode, a direct connection between said second grid and ground, a connection including a resistance of relatively high value extending from said screen grid to the positive terminal of a source of

unidirectional potential whose negative terminal is connected to ground, a resistor of relatively low value connected between said cathode and ground, a parallel tuned output circuit connected between said anode and the positive terminal of a source of polarizing potential, a capacity feed-back circuit devoid of inductive coupling effects connected between said anode and first grid, and a resistor connected between said first grid and ground.
